UNITED STATES PATENT OFFICE.

FREDERIC AUMONIER, OF LONDON, ENGLAND.

DESIGN FOR WALL-PAPER.

SPECIFICATION forming part of Design No. 22,804, dated September 26, 1893.

Application filed August 28, 1893. Serial No. 484,265. Term of patent 3½ years. Patented in England March 3, 1893, No. 208,524.

To all whom it may concern:

Be it known that I, FREDERIC AUMONIER, (trading as WM. WOOLLAMS & Co.,) a subject of the Queen of Great Britain, and a resident of 110 High Street, near Manchester Square, London, England, have invented a new and original Design for Wall-Paper, (patented in Great Britain, No. 208,524, on the 3d of March, 1893,) of which the following is a specification.

5 **10** This design for wall-paper with frieze as shown on the annexed drawing consists of acanthus leaves intertwined in curvular form

the frieze being acanthus leaves arranged spirally. An ornamental beading is above and below the frieze.
